REGENERATION OF EXHAUSTED SILVER
BLEACHING SOLUTIONS

Robert H. Zappert, Binghamton, N. Y., assignor
to General Aniline & Film Corporation, New
York, N. Y., a corporation of Delaware

No Drawing. Application December 30, 1949,
Serial No. 136,145

10 Claims. (Cl. 95—88)

1

This invention relates to a photographic process and more particularly to the process of regenerating exhausted silver bleaching solutions.

In the processing of color film it is customary to convert the silver, formed by development, into a hypo-soluble silver salt, such as silver bromide which is subsequently removed by fixing. A similar procedure is involved in removing negative silver in processing black and white reversal film. The most commonly employed silver bleaching solution consists essentially of an aqueous solution of an alkali ferricyanide and an alkali bromide, and if desired, small amounts of a buffer or a bleaching accelerator, such as the phenoxyethanol described in United States Patent 2,419,900.

The bleach solutions, although reasonably stable during storage, lose their efficiency as soon as they have been used for the treatment of relatively small areas of film. Subsequent bleaching with the used solution not only requires considerably more time but the removal of silver is incomplete, causing dulling of the highlights together with unsightly stain. Replenishments of the customary procedures, such as by the addition of ferricyanide and potassium bromide, which are used up in the bleaching reaction, does not improve the performance of an exhausted bleach solution to any appreciable extent. The analysis of such a solution intended for discard usually indicates that as much as 90 to 95% of the alkali ferricyanide originally added is still present. It becomes manifest that a procedure utilizing only a small fraction of an active ingredient is not only wasteful but economically unsound, particularly where as here, the active ingredient, the ferricyanide, is relatively expensive.

It is, therefore, an object of the present invention to provide a simple and economical method of regenerating an exhausted ferricyanide bleach solution.

Other objects and advantages will appear hereinafter.

According to the present invention, exhausted bleach solutions comprising an alkali ferricyanide and an alkali bromide are regenerated or rejuvenated by the action of a reagent or mixture of reagents capable of releasing elementary bromine in aqueous solutions. It has been recognized that the slowing up of the bleaching rate of an exhausted silver bleach solution is caused by the formation of ferrocyanide ions and by the loss of bromide ions. The action of bromine on an exhausted bleach solution appears

5 to perform a dual function (1) by oxidizing the ferrocyanide ions to ferricyanide ions, and (2) by supplying additional bromide ions. Bromine, itself or its solution in water commonly known as bromine water, performs a similar function but tends to destroy some of the ferricyanide. Moreover, bromine gives off highly objectionable toxic vapors and must be handled with extreme care in order to avoid serious burns. In addition, if accidentally spilled, it may seriously affect not only the film but also tanks, spools, and similar equipment utilized in the film processing.

10 I have found that reagents or mixtures of reagents containing bromine as a hypobromide or a bromate-bromide mixture and which release bromine after addition to the exhausted bleach solution may be employed to overcome the foregoing disadvantages. Reagents of this type are the alkali metal hypobromides, i. e., sodium, potassium or lithium hypobromide, a mixture of an alkali metal bromate and hydrobromic acid in the molar ratio of 1:6, and a mixture of an alkali metal bromate and alkali metal bromide 15 in a molar ratio of 1:5, and containing in addition approximately 6 to 7 mols of either sulfamic acid or an anhydrous alkali bisulfate. The anhydrous alkali bisulfate may be replaced by 20 approximately 3.5 mols of sulfuric acid diluted with a sufficient amount of water to make approximately a 20% solution.

25 The amount of the alkali metal hypobromide or mixture of alkali metal bromate and hydrobromic acid, and the like, is such as will release one molar equivalent of bromine for each molar equivalent of ferrocyanide present in the exhausted bleach. The actual or approximate amount can, therefore, be determined stoichiometrically after the determination of the ferrocyanide content by colorimetric, potentiometric, or other suitable titration means. Amounts of the reagent or molar equivalent mixture thereof smaller than the molar equivalent of ferrocyanide present in the exhausted bleach bath 30 give incomplete regeneration, whereas any appreciable excess tends to destroy some of the ferricyanide. A small excess can, however, be tolerated in most instances without impairing the efficiency of the regenerated bleach solution.

35 As is well known all photographic bleach solutions contain an alkali metal ferricyanide, such as lithium, potassium or sodium ferricyanide as an oxidizing agent dissolved in a suitable solvent, such as, for example, water with or without the presence of other adjuvants. A typical bleach

solution consists of about 100 grams of an oxidizing agent per liter of solution and may contain one or more of the following ingredients:

Alkali metal bromide, such as lithium, potassium and sodium bromide	10 grams (converting agent)
Dialkali metal phosphate	40 grams (buffering agent)
Alkali metal bisulfate or organic acid, such as citric acid	5 grams (buffering salt)
Alkali metal tetraphosphate	20 grams (corrosion preventative)
Water to make	1 liter (solvent)

By an oxidizing agent, I mean any alkali metal ferricyanide that will oxidize a metallic silver image to form a silver salt. Most commonly used oxidizing agents are alkali metal ferricyanide, such as lithium, potassium, and sodium ferricyanides or mixtures of these salts.

By a converting agent, I mean a compound such as an alkali metal bromide which by reason of a difference in solubility will replace the silver ferricyanide formed in the bleaching reaction to form silver bromide and thus impel the bleach reaction to completion. Converting agents are sometimes called halogenizing agents.

By buffering agents, I mean a substance that is added to bring the ferricyanide bleach solution to a specified pH and to maintain this pH even though small amounts of acids or alkali may be carried into the bleach of the film. The pH of the solutions used in bleaching films are maintained between 3 and 9, although a pH between 5 and 7 is generally preferred.

By solvent, I refer to such liquid in which the above materials are dissolved and which is usually water.

By corrosion preventatives, I refer to those compounds which retard the corrosion of the ferricyanide bleach on developing tanks, trays and the like. Large quantities (20 to 80 grams per liter) of alkali metal phosphate, such as disodium phosphate sodium tetraphosphate, and the like have been found to prevent corrosion effectively.

The following examples describe in detail, methods for accomplishing the above objects, but it is understood that they are inserted merely for the purpose of illustration and are not to be construed as limiting the scope of the invention.

Example I

A photographic bleach solution having the following formula:

	Grams
Potassium ferricyanide	100
Potassium bromide	15
Dibasic sodium phosphate	40
Sodium bisulfate	25
Water to make	1 liter.

was used for the bleaching of 45 feet of 35 mm. color developed reversal film.

Photographic tests on sensitometric strips showed that the bleaching rate of the used or exhausted bleach solution, dropped below the practical limit and that even extended bleaching of a small length of color developed 35 mm. reversal film failed to remove the residual silver stain.

The ferricyanide ion concentration of the exhausted bleach solution was determined, according to the method of Brunner, Means and Zappert, described in the Journal of the Society of Motion Picture Engineers, vol. 53, page 30, and found to be 8.5 grams per liter.

A solution of sodium hypobromide prepared by

adding 10 ml. of bromine to 240 ml. of 2-N sodium hydroxide was used as the replenishing agent. The active bromine content of this solution was determined iodometrically in acid solution. 25 ml. of sodium hypobromide solution, a volume calculated from the results of the analysis as the chemical equivalent of the ferrocyanide present, was added to the exhausted bleach solution. The pH of the mixture was adjusted to approximately 8.5. After the solution had been standing for a short while, the pH was readjusted to 6.5 by the addition of dilute sulfuric acid.

Photographic tests showed that the bleaching action of the rejuvenated bleach was equal to that of a fresh solution.

Example II

One liter of a fresh bleach solution prepared as in Example I was used for the bleaching of 50 feet of color developed 35 mm. film. After bleaching, the solution showed signs of exhaustion and upon colorimetric analysis indicated a ferrocyanide ion concentration of 10 grams per liter.

In one liter of the exhausted bleach solution, 1.31 grams (1/6 molar equivalent) of potassium bromate were first dissolved and then 19 mls. (1 molar equivalent) of 20% hydrobromic acid added with stirring. After standing for less than 10 minutes, the solution was completely rejuvenated and showed excellent bleaching properties. The pH of the regenerated solution did not require adjustment.

Example III

One liter of an exhausted bleach solution, of the same composition as in Example I, was analyzed by iodometric titration and found to contain 10 grams of ferrocyanide ion per liter. The bleach solution was regenerated by adding, successively, a solid mixture of 1.31 grams (1/6 molar equivalent based on the amount of ferrocyanide in the bleach) of potassium bromate and 4.68 grams (1/6 molar equivalent) of potassium bromide, followed by the addition of 5.66 grams (1 molar equivalent) of anhydrous sodium bisulfate. Within a few minutes, the solution was completely rejuvenated and did not require any further adjustment of its pH.

Example IV

Example III was repeated with the exception that 5.66 grams of anhydrous sodium bisulfate were replaced by 9.9 mls. of a 20% aqueous solution of sulfuric acid. The exhausted bleach solution was completely rejuvenated and did not require any further adjustment of its pH.

In the commercial processing of motion picture color film, the concentration of the various constituents of the bleach solution decreases gradually. Some water is brought into the bleaching tank by the wetted film and small quantities of the ferricyanide salts are carried away by the bleached film. This dilution in most cases does not materially affect the bleaching rate. If desired, the solution can, however, be kept at full strength by adding small amounts of the same constituents or chemicals originally used for the preparation of the bleach solution.

As many apparently widely different embodiments of this invention may be made without departing from the spirit and scope thereof, it is to be understood that I do not wish to limit myself to the specific embodiments thereof except as defined by the appended claims.

I claim:

1. In the photographic process of bleaching a metallic silver image to silver halide with a bleach solution comprising an alkali metal bromide and ferricyanide whereby the silver in the silver image is oxidized to silver ions which combine with the halide ions of the solution and form a silver halide in the emulsion and a relatively small amount of the ferricyanide is reduced to ferrocyanide, and then regenerating the spent 10 bleach solution by adding a regenerating agent, the improvement wherein said regenerating agent is a material selected from the group consisting of an alkali metal hypobromide, a mixture of alkali metal bromate and hydrobromic acid in the molar ratio of 1 to 6, and a mixture comprising an alkali metal bromate and an alkali metal bromide in the molar ratio of 1 to 5, the amount of said material being such as that which 15 will release one molar equivalent of bromine for each molar equivalent of ferrocyanide ion present in the exhausted bleach solution.

2. A process according to claim 1, wherein there is added an amount of an alkali metal hypobromide in a quantity sufficient to release one molar equivalent of bromine for each molar equivalent of ferrocyanide ion present in the exhausted bleach solution.

3. A process according to claim 1, wherein there is added an amount of a mixture of an alkali metal bromate and hydrobromic acid in the molar ratio of 1 to 6 in a quantity sufficient to release one molar equivalent of bromine for each molar equivalent of ferrocyanide ion present in the exhausted bleach solution.

4. A process according to claim 1, wherein there is added an amount of a mixture comprising an alkali metal bromate and alkali metal bromide in the molar ratio of 1 to 5 in a quantity sufficient to release one molar equivalent of bromine for each molar equivalent of ferrocyanide ion present in the exhausted bleach solution.

5. A process according to claim 1, wherein there is added an amount of sodium hypobromide in a quantity sufficient to release one molar equivalent of bromine for each molar equivalent of ferrocyanide ion present in the exhausted bleach solution.

6. A process according to claim 1, wherein there is added an amount of a mixture of potassium bromide and hydrobromic acid in the molar ratio of 1 to 6 in a quantity sufficient to release one molar equivalent of bromine for each molar equivalent of ferrocyanide ion present in the exhausted bleach solution.

7. In the photographic process of bleaching a metallic silver image to silver halide with a bleach solution comprising an alkali metal bromide and an alkali ferricyanide whereby the silver image is oxidized to silver ions which combine with the halide ions of the solution and form a silver halide in the emulsion and a relatively small amount of the ferricyanide is reduced to ferrocyanide, and then regenerating the spent

bleaching solution by adding a regenerating agent, the improvement wherein said regenerating agent is a mixture of potassium bromate and potassium bromide in the molar ratio of 1 to 5 containing 6 to 7 mols of an alkali metal bisulfate in a quantity sufficient to release one molar equivalent of bromine for each molar equivalent of ferrocyanide ion present in the exhausted bleach solution.

8. In the photographic process of bleaching a metallic silver image to silver halide with a bleach solution comprising an alkali metal bromide and an alkali ferricyanide whereby the silver in the silver image is oxidized to silver ions which combine with the halide ions of the solution and form a silver halide in the emulsion and a relatively small amount of the ferricyanide is reduced to ferrocyanide, and then regenerating the spent 10 bleach solution by adding a regenerating agent, the improvement wherein said regenerating agent is a mixture of potassium bromate and potassium bromide in the molar ratio of 1 to 5 containing 6 to 7 mols of sulfamic acid in a quantity sufficient to release one molar equivalent of bromine for each molar equivalent of ferrocyanide ion present in the exhausted bleach solution.

9. In the photographic process of bleaching a metallic silver image to silver halide with a bleach solution comprising an alkali ferricyanide and an alkali metal bromide whereby the silver in the silver image is oxidized to silver ions which combine with the halide ions of the solution and form a silver halide in the emulsion and a relatively small amount of the ferricyanide is reduced to ferrocyanide, and then regenerating the spent 15 bleach solution by adding a regenerating agent, the improvement wherein said regenerating agent is a mixture consisting of an alkali metal bromate and an alkali metal bromide in the molar ratio of 1:5 and which said mixture of the alkali metal bromate and alkali metal bromide contains 3 to 3.5 mols of sulfuric acid dissolved in a sufficient amount of water to make a 20% aqueous solution.

10. The process according to claim 7 wherein the alkali metal bisulfate is sodium bisulfate.
